DESIGN FOR AN ASH TRAY

Joseph Melillo, Great Neck, N. Y., assignor to De
Groodt & Associates, Inc., Woodhaven, N. Y.

Application January 6, 1947, Serial No. 135,967

Term of patent 3½ years

(Cl. D85—2)

To all whom it may concern:

Be it known that I, Joseph Melillo, a citizen of the United States of America and a resident of Great Neck, Long Island, New York, have invented a new, original, and ornamental Design for an Ash Tray, of which the following is a specification, reference being had to the accompanying drawing, forming a part thereof.

Fig. 1 is a front perspective view of an ash tray, showing my new design;

Fig. 2 is a top plan view thereof;

Fig. 3 is a side elevational view thereof; and
Fig. 4 is a rear view on a reduced scale.

I claim:

The ornamental design for an ash tray, substantially as shown and described.

JOSEPH MELILLO.
